UNITED STATES PATENT OFFICE.

EDGAR B. JEWETT, OF BUFFALO, NEW YORK.

DESIGN FOR A TABLE AND REFRIGERATOR.

41,221.

Specification for Design.

Patented Mar. 7, 1911.

Application filed October 20, 1910. Serial No. 588,225. Term of patent 14 years.

To all whom it may concern:

Be it known that I, EDGAR B. JEWETT, a citizen of the United States, residing at Buffalo, in the county of Erie and State of New York, have invented a new, original, and ornamental Design for a Table and Refrigerator, of which the following is a specification, reference being had to the accompanying drawing, forming part thereof.

The drawing is a perspective view showing my new design.

I claim:

The ornamental design for a table and refrigerator, as shown.

EDGAR B. JEWETT.

Witnesses:

M. R. PHILLIPS,
O. D. JAMIESON.

Copies of this design may be obtained for five cents each, by addressing the "Commissioner of Patents, Washington, D. C."
